UNITED STATES PATENT OFFICE.

AUGUST CHARLES ROSEN BROOK, OF WALL, SOUTH DAKOTA.

CAR-SEAL.

1,018,682.

Specification of Letters Patent. Patented Feb. 27, 1912.

Application filed March 21, 1911. Serial No. 615,836.

To all whom it may concern:

Be it known that I, AUGUST C. ROSEN BROOK, a citizen of the United States, residing at Wall, in the county of Pennington 5 and State of South Dakota, have invented new and useful Improvements in Car-Seals, of which the following is a specification.

This invention relates to improvements in seals of the class used on freight cars, baggage, etc., and particularly to that type of 10 seals which will indicate, upon mere inspection, whether the same has been tampered with.

The object of the invention is to provide 15 a simple, cheap and efficient type of seal which locks automatically, in which the lock when closed, is entirely concealed, and in which it is impossible to tamper with the lock of the closed seal without visual evidence of that fact being given.

The invention consists of the features of 20 construction, combination and arrangement of parts, hereinafter fully described and claimed, reference being had to the accompanying drawings, in which:

Figure 1 is a perspective view of the closed seal. Fig. 2 is a central longitudinal section thereof. Figs. 3 and 4 are transverse sections on the lines 3—3 and 4—4 of Fig. 2. 25 Figs. 5 and 6 are sectional plan views on the lines 5—5 and 6—6 of Fig. 3. Fig. 7 is a view of the housing sleeve partially spread open. Fig. 8 is a view of the extremities of the seal.

Referring to the drawing, the numeral 1 30 designates a blank or strip forming the body of the seal, and made of malleable tin or other suitable material, said strip being bent into loop form to provide arms 2 and 3, 35 which, for convenience of description, will be termed upper and lower arms.

The upper arm 2 is provided with a back-turned or looped extremity 4 having a T-shaped slot formed with a longitudinal portion 5 and a transverse portion 6 at the outer 40 end of said longitudinal portion. The front wall 7 of the slot portion 6 is bent or deflected laterally beyond one face of the strip to provide a bearing shoulder, while the 45 portions 8 of the strip at the points of intersection of the portions of the slot are bent or deflected laterally beyond the other face of the strip to provide bearing lips. As shown, the arm 2 is provided with a down- 50 bent transverse rib or indentation 9 formed 55 upon the upper or relatively free limb of

the looped portion thereof above the locked lower limb of said looped portion and arranged to overlie the latter at a point slightly in advance of the slot portion 6 and 60 between the same and the free edge 10 of said lower limb.

The arm 3 of the strip is provided at its extremity with a T-shaped slot having a longitudinal portion 11 and a portion 12. The 65 outer edge or wall 13 of the slot portion 12 is bent or offset laterally beyond one face of the strip, while the portions of the strip at the points of intersection of the slot portions are bent or offset laterally beyond the 70 other face of the strip to provide bearing lips 14.

An elongated flattened housing sleeve or tube 15 is provided to receive the ends of the arms 2 and 3 and to interlock therewith to 75 close the seal and conceal the lock in such manner that the lock can not be tampered with for the purpose of opening the seal without giving visual evidence of such fact. This sleeve is formed of an oblong rectangular piece of tin or other suitable material 80 folded to form an upper wall 16 and a lower wall 17, the latter being composed of the free longitudinal edges of the strip which are arranged in substantially abutting relation.

The sleeve is open at each end and is provided upon the interior thereof, adjacent its inner and outer ends, respectively with pairs 85 of substantially triangular locking wings 18 and 19, having their longitudinal side edges respectively diverging inwardly from the proximate ends of the sleeve. The wings are integrally joined at their inner ends to the edges of the sections of the walls 17 by 90 parallel upright flanges 18 and 19 and are bent laterally in an outward direction from said flanges so as to lie parallel with the walls 16 and 17.

In assembling the parts of the seal, the 100 end of the arm 2 is first inserted into the outer or rear end of the casing and brought into interlocking engagement with the wings 19, by which it is automatically locked therein against any possibility of 105 withdrawal. In this locking action the extremity of the arm is brought by the offsetting of the portions 7 and 8 into such position that as the strip is inserted the shoulder 7 will pass above and ride over the 110 wings, while the lips 8 will pass beneath the wings so that the flanges 19^a will be received

in the slot 5. When the extremity is inserted to its fullest extent, the inner end wall of the slot portion 5 will abut against the outer ends of said flanges, at which time 5 the shoulder 7 will pass beyond and spring downward into interlocking engagement with the inner ends of the wings, by which the wings will be caused to lie above the inserted end of the arm 2 and to lock the same 10 against possibility of withdrawal. After the end of the arm 2 has been inserted and locked in position, as above described, the said end 2 is passed from rear to front through the sleeve over the locking wings 15 and the strip drawn out until taut, whereby the bight or loop 4 will be formed in the arm 2, the upper portion of which loop will lie between the locked extremity of the loop and the upper wall 16 of the sleeve, 20 while the bight or closed end of said loop will fully close the outer or rear end of the sleeve. The seal is then ready for use in the usual manner. To close the seal, the free end of the arm 3 is inserted within the 25 inner or front end of the sleeve between the bottom wall of said sleeve and the upper arm and forced inward until its locking lip 13 engages the inner ends of the wings 18. In this operation, the lip 13 rides over the 30 wings and the lips 14 beneath the wings, while the slot portion 11 receives the flanges 18^a, the locking operation being the same as that described with respect to the wings 18 and free end of the arm 2, the ends of the 35 strip being thus securely locked within the sleeve, whereby the lock is concealed in such manner and the parts so held against release that disconnection cannot be effected without mutilation of the seal, thus giving 40 visual evidence of the fact that it has been tampered with.

It will be observed that the rib or indentation 9 bears upon the inner ends of the wings 19 and holds the upper fold or limb 45 of the inclosed portion of the arm 2 in contact with the wall 16, and at the same time presses the lower fold, limb or backturned portion 4 of said arm toward the wall 17, thus spacing said folds to permit the extremity of the arm 3 to pass freely between the same. By this construction the end of 50 arm 3, after interlocking with the wings 18, will be snugly received in the space between said folds of the arm 2 at a point between 55 sets of flanges and will abut against the rib 9, whereby the parts will be reinforced and compactly held within the housing sleeve.

The arms are provided with openings 20 with embossed or raised portions which are 60 adapted to register and to occupy a position close to the sleeve when the seal is closed, such openings and bosses serving as indi-

cators to show whether or not the device has been tampered with, that is, a part of the seal cut away and an effort made to hide or 65 cover up such work. Any letters or configurations to be imposed upon the seal should have their starting point inwardly of said openings.

Having thus described the invention, I 70 claim:

1. A car seal comprising a housing sleeve having spaced pairs of flanges provided with laterally extending tapered wings, and a strip having slotted end portions to respectively interlock with the pairs of flanges and wings. 75

2. A car seal comprising a housing sleeve provided with laterally extending tapered wings at each end thereof connected by parallel flanges with said sleeve, and a strip provided with T-slotted end portions to respectively interlock with the pairs of wings and the flanges thereof. 80

3. A car seal comprising a housing sleeve 85 having at each end thereof pairs of parallel flanges provided with laterally bent triangular wings, the side edges of the respective pairs of wings converging toward the adjacent end of the sleeve, and a strip provided with T-slotted end portions to respectively 90 interlock with the pairs of wings and the flanges thereof.

4. A car seal comprising a housing sleeve having at each end thereof pairs of parallel flanges provided with laterally bent triangular wings, the side edges of the respective pairs of wings converging toward the adjacent ends of the sleeve, and a strip provided with T-slotted end portions to respectively 95 interlock with the pairs of wings and the flanges thereof, the walls of the cross portions of each slot being deflected in opposite directions to respectively ride over and under the wings in the interlocking action. 100

5. A car seal comprising a housing sleeve having pairs of flanges adjacent the opposite ends thereof provided with locking wings, and a strip having T-slotted end portions to respectively interlock with the pairs 110 of wings and the flanges thereof, one end of said strip being looped and extending through the sleeve and having the relatively free limb of its looped portion provided with an offset to space it from the locked 115 limb thereof to form a guide for the insertion of the opposite end of the strip.

In testimony whereof I affix my hand in the presence of two witnesses.

AUGUST CHARLES ROSEN BROOK.
